COMBINATION CHAMPAGNE BOTTLE CORK AND SKIRT LOCK THEREFOR

Floyd A. Terwilliger, Rochester, N.Y.

Application October 24, 1958, Serial No. 53,132

Term of patent 14 years

(Cl. D58—10)

FIG. 1.

FIG. 2.

FIG. 3.

FIG. 4.

Fig. 1 is a side elevation of a combination champagne bottle cork and skirt lock therefor embodying my new design;

Fig. 2 is an axial section therethrough;
Fig. 3 is a top plan view thereof; and
Fig. 4 is a bottom view thereof.

I claim:

The ornamental design for a combination champagne bottle cork and skirt lock therefor, substantially as shown.
